CIRCULAR KNITTING MACHINE

Frederick Edward Deans and Charles Frederick Manger, Leicester, England, assignors to The Bentley Engineering Company Limited, Leicester, England

Application September 10, 1934, Serial No. 743,460
In Great Britain September 15, 1933

9 Claims. (Cl. 66—50)

This invention is for improvements in or relating to circular knitting-machines.

Circular knitting machines have heretofore been provided with needle-selecting mechanism for producing pattern and other effects in the knitted fabric by varying the normal operation of selected needles, such for instance as by causing said needles to form floated stitches, tuck stitches or the like, or in a rib-knitting machine, by varying the rib knitting by transferring such needles from one needle cylinder to the other.

An object of the present invention is to provide improved constructions of such needle-selecting mechanism, which are applicable to, but not necessarily limited in application to, machines of the multi-feed-point type.

In the constructions of needle-selecting mechanism hereinafter described as illustrative of the present invention, the said mechanism comprises a series of elements, hereinafter termed jacks, each adapted to be acted upon by a cam thereby to operate a needle or needle slider, a series of other elements, hereinafter termed selectors, adapted to act upon said jacks to vary the operative relation of the jacks with said cam, and pattern-controlled means for operating said selectors.

In the said constructions, the jacks are each rocked to engage or miss a cam which is adapted to move the jack to cause it to engage and move a needle slider. Also, in said constructions, the jack is located in the same needle trick in the needle cylinder as is the needle slider. In one of the said constructions, each selector is also situated within a needle trick and is moved lengthwise of the trick to rock the jack, but in another of said constructions, the selectors are in tricks which are other than the needle tricks and which are disposed at an angle to the needle tricks.

In the said constructions the pattern-controlled means comprises a drum having detachable cam pieces upon it, each of which pieces by rotation of the drum is adapted to move one of a series of machine elements to bring a cam incline thereon out of and into range of a butt on a selector so as, at times, to move the selector in its trick by reason of the butt moving over the cam incline as the operation of the machine carries these parts past each other.

In a machine of the multi-feed-point type as above referred to, usually each feed point of the machine will have a needle-selecting mechanism especially appropriated to it, but in certain circumstances such an arrangement is by no means essential. Thus, one of the needle-selecting

mechanisms can be dispensed with in the case of a machine having two feed points, when that machine is to effect patterning of the type which is produced when, in a given part of the knitted fabric, certain needles of a needle-group knit only at one of the feed points while the other needles of that needle-group knit only at the other feed point. In such a case the effect produced at one feed point by a needle-selecting mechanism appropriated to that feed point can be reversed at the other feed point by a suitable arrangement of cams.

The present invention provides also an improved cam assemblage for the jacks above referred to which assemblage includes an arrangement of cams by means of which the setting given to the jacks by the pattern means for the operation of the needles at one feed point is reversed for the operation of the needles at another feed point.

The said illustrative constructions, including a convenient form of cam assemblage for the jacks as above referred to, will now be described with the aid of the accompanying drawings, and will be assumed, by way of example, as applied to the well-known superposed cylinder type of machine which is exemplified by the machines described in the specifications of British Letters Patent Nos. 15,008/1900, 24,290/1912 and 171,483, the machine being assumed to be one in which the needle cylinders rotate within the stationary cam boxes. The features of the invention are pointed out in the appended claims.

In the accompanying diagrammatic drawings:—

Figure 1 is a development of the said cam assemblage for the jacks as seen from the interior of the cam box;

Figure 2 is a perspective view of the cams shown in Figure 1, certain of the jacks being shown also;

Figures 3 and 4 are perspective views of two of the cams seen in Figure 2, but viewed from a different station from that from which they are seen in Figure 2;

Figure 5 is a perspective view of part of a circular knitting machine, having applied thereto, one construction of needle-selecting mechanism according to the present invention;

Figure 6 is a plan of certain of the parts shown in Figure 5;

Figure 7 is a sectional elevation of parts seen in Figure 6;

Figures 8 and 9 are detail views showing, respectively, a jack and a selector in two different positions;

Figure 10 is a detail view of means for operating a selector;

Figure 11 shows another construction of needle-selecting mechanism according to this invention;

Figure 12 is a development of cams in the lower cam box of the machine as seen from the interior of the cam box in a construction in which at each of two feed points of the machine needle-selecting mechanism as shown in Figures 5 to 9 or as shown in Figure 10 is employed;

Figure 13 is an inverted plan of certain of the cams shown in Figure 12; and

Figure 14 is a development of cams in the lower cam box of the machine as seen from the interior of the cam box in a construction in which the cam arrangement for the jacks as shown in Figures 1 and 2 is employed, thereby necessitating the need of a needle-selecting mechanism at but one of the two feed-points of the machine.

The machine illustrated in the drawings comprises a circular bed plate 70 which is secured to the frame of the machine. Above the bed plate 70 and held spaced therefrom by means including pillars 72 is a second bed plate 74 by which the cam box 76 for the lower or plain needle cylinder 78 is supported. The needle cylinder 78 is rotated about its axis by connections from the main shaft of the machine, said connections including a gear wheel 80 (Figure 7) which is attached to the lower end of the needle cylinder 78.

The first of said constructions comprises a pattern drum 82 (Figure 5) located on the outer side of and near the bottom end of the plain needle cylinder 78, and adapted to rotate about an axis parallel with the axis of said cylinder. The pattern drum 82 is rotatably mounted upon a stud 84 (Figure 7) projecting upwardly from a plate 86 secured to the bed plate 70 and comprises an inner core-like portion 88 surrounded by an outer shell 90, the two parts 88 and 90 being secured together by screws 92. The pattern drum is held frictionally against unwanted movement by a spring 94 in compression between two washers 96 and 98 loose on the stud 84, the upper washer 96 being backed up by a nut 100 by the turning of which the degree of compression of the spring 94 can be adjusted. The pattern drum 82 is intermittently rotated by a pawl-and-ratchet mechanism comprising a ratchet wheel 102 (Figure 5) secured to the lower end of the drum, the teeth of which ratchet wheel are engaged by a pawl 104, pivotally mounted upon a lever 106 that can swing about the drum axis and is actuated by a cam 108 carried upon the gear wheel 80. Suitably arranged springs 110 and 112 maintain, respectively, the pawl 104 in engagement with the ratchet wheel 102 and the lever 106 in the path of the cam 108.

The peripheral surface of the pattern drum 82 is adapted to support a number of detachable pins or cam pieces 114, to which end the outer shell 90 of the drum is provided with a number of holes 116 arranged in rows extending around the drum, there being in the present instance fourteen tiers of rows of these holes. In these holes, pins or cam pieces 114 are inserted in accordance with the pattern to be produced in the knitted fabric. Pivoted upon a post 118 (Figure 6) arranged parallel with the drum axis, is a series of spring-pressed levers 120, fourteen in number (see Figure 5) to agree with the number of tiers of holes 116, each of which levers has a pointed end 119 which is located closely adjacent the drum periphery and overlying one of the rows of holes

116; this end 119 of the lever will accordingly be lifted, i. e. moved away from the drum, as the pattern drum rotates, by a cam piece or pieces 114 present in that row. The other end 121 of each lever 120 has a cam incline 122 formed upon it which, when the pointed end 119 of said lever is not lifted by a cam piece 114 in said row of holes is in the path of movement (due to rotation of the needle cylinder) of a butt 123 on a selector 124 in a needle trick 125 in the needle cylinder 10 78. The selector 124, which will presently be described, is raised by the action of the cam incline 122 on the butt 123. When the pointed end 119 of the lever 120 is lifted by a cam piece 114 on the pattern drum periphery (see Figure 10), the cam incline 122 on the other end of the lever is removed from the path of the butt 123, and consequently the selector 124 is not raised.

A selector 124 is associated with each of the needles 126 (Figure 7) which is concerned in the 20 selecting operation. This selector is located in the needle trick 125 below the usual needle slider 127, but between each slider 127 and the selector 124 there is situated in the trick 125 a jack 128, presently to be described. In general appearance the selectors resemble the usual needle sliders, that is to say they are relatively long and thin pieces of metal adapted to be received in and moved to and fro along the needle tricks in the cylinder. Each selector has two butts 128 30 and 129 of which the butt 129 is in the same relative position on all the selectors, and is employed to return the selector to an initial position should it have been displaced therefrom in the selecting operation. This butt 129 for this purpose is acted upon by a cam 131 on the cam box 76. The second butt 128 of the two butts mentioned is in a different position in different selectors, but in any given selector, the position of this butt 128 is such that when the selector is in 40 said initial position the butt 128 will be engaged by the cam incline 122 on one of the fourteen levers 120, if the pointed end 119 of that lever is not in engagement with a cam piece 114 on the pattern drum. Near its upper end each selector has a short offset portion 132 extending outwardly from the needle cylinder, followed by an upwardly-extending portion 133, the inner side of which (i. e. the side nearer the needle cylinder) has formed upon it an incline which 50 gives to the selector a somewhat pointed upper end 134. This pointed end is adapted to engage and rock a jack 128 which is situated in the trick immediately above the selector. Each jack has two butts 135, 136 adapted to be engaged, 55 respectively, by two cam surfaces 137, 138 formed upon a cam block in the cam box 76 of the machine. The two butts 135, 136, on the jack 128 are at different levels, the upper butt 135 extending outwardly and (at times) over the cam 60 surface 137, and the lower butt 136 projecting upwardly in front of the cam surface 138. Below the lower butt 136 the jack slopes downwardly and inwardly in an incline 139 which is adapted to be engaged by the pointed upper end 65 134 of the selector; and below the incline 139 on the jack, the jack has a short stem 140, rounded at its bottom end, which normally is situated behind the upper end of the selector, in the recess afforded by the offset portion 132 of the selector. 70

The function of the jack 128 is to raise a needle slider 127 to a level at which it will come under control of the usual cams in the cam box 76 so that the needle associated with the slider will perform its normal operations. To perform this 75

function the jack 128 is raised by the engagement of its upper butt 135 with the cam surface 137, and lifts the needle slider 127 by engagement of the bottom of said slider by the top end 5 of the jack. Having performed this duty, the jack is later returned to its initial position by a third cam surface 141 on the cam block which surface engages a part of the jack between its two butts 135 and 136. When in the selecting 10 operation a needle is not to be lifted as just described, a selector 124 (see Figures 8 and 9) will be raised by the means previously stated, and its pointed upper end 134 will engage the incline 139 on the jack 128 and rock the jack inwardly and remove its upper butt 135 from over the cam surface 137. Later in the operation of the machine the jack is moved outwardly again by the action of the cam surface 138 upon the lower butt 136 of the jack.

Centrifugal action due to rotation of the needle cylinder 78 tends to move the jacks 128 outwardly and thus tends to maintain the upper butt 135 of each jack in full engagement with the cam surface 137. To assist this action the cam surface 137, in cross-section, inclines downwardly and outwardly somewhat, and the lower edge of the upper butt 135 has a corresponding inclination. At the part of the said upper surface 137, however, at which the jack 128 is moved inwardly by the action of its selector, the upper surface 137 of the cam block is substantially horizontal (in cross-section) or even slightly reversely inclined, so as to permit the jack under action of its selector to be moved inward easily at this part of said surface. Immediately following this part of said surface (considered in relation to the direction of rotation of the needle cylinder) the surface rises a distance sufficient to come in front of the upper butt of a jack that has been pushed back by its selector and thus keep that jack in its inward position until it has safely passed the rise on said upper cam surface 137 which is employed to give to a jack its needle-slider-lifting movement. This cam formation, it will be appreciated, completely segregates those jacks which are to remain inoperative from those which are to perform their slider-lifting function.

Among the advantages possessed by a construction according to this invention are the following:—

The selectors 124 having only to control the position of the jacks 128 need move but a short distance (say one-sixteenth of an inch) compared with the relatively longer distance (some quarter of an inch) which the jacks have to move to ensure that the needle-sliders 127 controlled by them shall properly engage the cams which act upon the needle-sliders; if by accidental movement of a selector 124 a jack that should 50 not have been acted upon is moved inwardly, so that at least its upper butt 135 only just engages the cam surface 137, centrifugal action and the shapes of that surface and of the butt as aforesaid will move the jack outwardly again so that its butt fully engages said surface; the position 55 in which the pattern drum 82 can be placed is variable within relatively wide limits considering that the point in the needle circle at which the selectors 124 are moved by the action of the pattern drum need not of necessity be closely adjacent the point in said circle at which the jacks 128 act upon the needle sliders 127; and the layout 60 of the cam pieces 114 on the periphery of the pattern drum 82 determines which needles shall 65 knit, for, as pointed out hereinbefore, the cam 70 75

pieces 114 acting on the pointed ends 119 of the levers 120 remove the inclined ends 122 of said levers from the path of the butts 123 on the selectors 124 and as a consequence the selectors remain idle, and thereby permit a jack 128 to move 5 its needle slider 127 to a position in which, in due course, it reaches the stitch cam.

The two advantages last mentioned are of importance in connection with the multi-feed-point type of machine previously referred to, an example of which type of machine is described in application Serial No. 667,444 filed April 22, 1933. Thus, in such a machine having two feed points (a main feed point and an additional feed point) a needle-selecting-mechanism according to the present invention can be provided for each feed point. These mechanisms can be placed at any convenient points in the needle circle (usually towards the back of the machine) and each will show by the lay-out of the detachable cam pieces 20 on its pattern drum the needles which are to knit at the particular feed point to which that mechanism is appropriated.

In one construction of cam assembly for a machine as just referred to, the stitch cam 150 (Figure 12) for the additional feed point is a pattern-controlled bolt cam adjustment of which bolt cam can be such as to cause the knitting butts 151 of the needle sliders to miss said stitch cam 150 and be engaged only by the stitch cam 152 at the main feed point when knitting at the additional feed point is not to occur. The track followed by the knitting butts 151 at this time is indicated at 153. When knitting is to take place at both feed points, the cam 150 is moved inwardly of the needle cylinders 25 so as to engage the knitting butts 151 which then follow the track 154 in the vicinity of the additional feed point, so that knitting occurs at that feed point also. Preceding the stitch cam 152, in the direction of rotation of the needle 30 sliders, is a pattern-controlled bolt cam 155, which may be termed a pilot cam, and preceding the stitch cam 150 is a similar pilot cam 156. Each of the pilot cams 155, 156 is located at a point in the needle circle at or preferably slightly 35 in advance of the point where the rise (indicated at 158 or 159 in Figure 12) on the cam surface 137 is situated, which gives to the jacks 128 as 40 aforesaid their needle-slider-lifting movement.

Patterning is usually performed at both feed 45 points and when patterning is to begin both of the pilot cams 155 and 156 are withdrawn into inoperative position. In the patterning operation a needle slider 127 (which moves from right to left in Figure 12) in passing the position of the 55 pilot cam 155 will either be lifted by its associated jack 128 so that its knitting butt 151 travelling in the left-hand portion of the track 154 reaches the track 153, which later brings it to the stitch cam 152 of the main feed point, or the needle 60 slider is not so lifted with the result that its knitting butt passes along an idle track 160 which brings it to the stitch cam 152 at a non-knitting level. The course the needle slider takes, depends upon a previous selective action on its jack 65 128 by the selector 124, which is associated with that jack. If, for instance, the jack has been pushed inwardly by its selector, under action of the selecting mechanism for the main feed point, which mechanism is located at 162 (Figure 12), 70 the upper butt 135 of the jack will have been removed from over the cam surface 137 and consequently the jack and its needle slider will not be lifted by the rise 158. If, on the other hand, the action of the said needle-selecting mechanism has 75

been such as not to actuate the selector, the upper butt of the jack will remain over the cam surface 137 and the jack will be lifted by the rise 158 and in turn will lift its needle slider. The needle slider, whether it has been acted upon by the main stitch cam 152 or has travelled along the idle track 160, in its continued movement next passes the position of the pilot cam 156. Here again, it either is lifted by its jack (by the action thereon of the rise 159) into the track 153 which brings it to the additional stitch cam 150 or it is allowed to pass along the idle track 160 in which it passes the stitch cam 150 at non-knitting level, according to the setting of the jack by the needle-selecting mechanism appropriated to the additional feed point, which mechanism is located at 164 (Figure 12). Thus, in the present construction, any given needle by the action of the two needle-selecting mechanisms upon the jack associated with the slider for that needle, can be caused to knit at both feed points, to knit at either feed point to the exclusion of the other, or to knit at neither feed point.

In Figure 12, the double line 166 represents the position in respect to the needle circle, at which a jack and its associated needle slider have reached just after the upper butt 135 of the jack has run up the rise 158. The rising movement thus imparted to the jack has lifted its needle slider so that the knitting butt 151 thereof has been brought into the track 154 which it would have followed had the pilot cam 155 been in operative position. The knitting butt 151 next follows the track 153 leading to the stitch cam 152. The jack is now returned to its lower level again by the cam surface 141 which, as aforesaid, acts upon a part of the jack between its butts 135 and 136, as will be evident from an inspection of Figure 7; and the jack is now in readiness to be acted upon or otherwise by its associated selector at the station 164 at which the needle-selecting mechanism for the additional feed point is located. The double line 168 (Figure 12) represents the position of a jack and its associated needle slider after that jack has been acted upon by a selector at the station 162. At this station, the selector 124 was raised by the cam incline 122 on the associated lever 120 aforesaid, and pushed the jack 128 inwardly so as to remove its upper butt 135 from off the cam surface 137. The cam surface 137 at this part 170 thereof is recessed somewhat as previously explained so that the butt 135 can be moved readily from said surface, and immediately adjacent said part 170, also as previously explained, there is a slight rise 172, which maintains the jack in its inward position. This slight rise 172 is not sufficient to cause a jack which has not been pushed back to engage and move its associated needle slider. At the position 168, it will be noted that the knitting butt 151 of the needle slider is in the idle track 160 and consequently the needle of that slider will not knit at the main feed stitch cam 152. The jack that was pushed back will be returned to its original lower and outward position, soon after it passes the line 166, by the cam surface 141 and by the cam surface 138 which, as aforesaid, acts upon its lower butt 136. The jack is now in readiness for selection or otherwise at the station 164, at which the selecting mechanism for the additional feed point is located.

In pattern production it frequently happens that in a given part of the fabric needles which knit at the main feed point do not knit at the additional feed point while those which do knit

at the last-named point do not knit at the main feed point. The action of each needle-selecting mechanism in this particular instance is the converse of that of the other. It will be appreciated that in the present construction each jack, after having been set by one selecting mechanism and after having acted according to that setting, is returned to a neutral position in readiness to be reset by the second selecting mechanism. In the type of patterning just referred to the setting of any jack by one selecting mechanism is the converse of the setting of that jack by the other selecting mechanism. Hence, for this particular type of patterning, one of the selecting mechanisms can be dispensed with and cams or the like provided for reversing the setting which the remaining single selecting mechanisms has given to the jacks. In Figures 1, 2, 3, and 4, a convenient cam assemblage for the jacks for the above purpose is shown, while in Figure 14, the relation of this assemblage to the rest of the cams in the lower cam box is illustrated. In the following description it will be assumed that the jacks move from right to left in the direction indicated by the arrow in Figure 1, and that they are situated in the needle tricks of the needle cylinder and acted upon by selectors as previously described.

The position in the needle circle at which the selectors are adapted to act upon the jacks is indicated at 10. In the operation of the machine, the upper butts 12 of those jacks which have been rocked inwardly by their selectors so that said butts are removed from over the surface 15 of the cam block 16, pass behind the raised part 35 14 of the cam block 16, as is shown by the jack 18 (Figure 2). These jacks as they travel round with the needle cylinder remain at the level at which the jack 18 is shown, see the jack 20, until after they have passed the cam block 26. On 40 the underside of the cam block 26 there is a cam 28 (see Figure 4), which engages the lower butt 30 of each of these jacks and moves the jacks outwardly as is shown by the jack 22. The upper butts 12 of these jacks now pass over the surface 45 32 of the cam block 34, run up the incline 36, pass over the surface 38 and then up the incline 40 (see the jack 24) at which latter point these jacks engage their needle sliders and lift them into the range of their operating cams. These jacks are 50 later returned to their initial level by a cam on the underside of the cam block 16 which engages the part 140 of each jack.

The upper butts 12 of those jacks which have not been rocked inwardly by their selectors at the point 10, run up the incline 42 on the block 16, then pass along the adjacent upper surface 44 of said block, then along the surface 48 of cam block 50, see jack 17, after which the upper butts run up the incline 52, see jack 19, at which point 60 these jacks engage their needle sliders and lift them into range of their operating cams. After passing up the incline 52, these jacks are rocked inwardly by the action on the outer ends of their upper butts of the inwardly-inclined surface 54 65 of cam block 56, see jack 21. These jacks are next lowered, see Jack 23, by the action on the upper ends of their lower butts 30 of the incline 60 on the block 56 and are still further lowered by the incline 62 on the block 34, which incline 70 also acts upon the upper ends of their lower butts. The jacks are thus brought to a level which is shown by the jack 25.

Thereafter, these jacks are returned to their initial position with their upper butts over the

surface 15 of the block 16, by means of a cam 46 on the underside of said block which, see Figure 3, acts upon their lower butts 30.

In order that the upper butts of these jacks shall be able safely to cross the gap above the surfaces 32 and 36 of the block 34, (which gap must be wide enough to accommodate an upper butt considering that the upper butts of some of the jacks have to pass through it) the outer faces 10 64 of the upper butts 12 are somewhat inclined downwardly and inwardly. This construction ensures that during travel of the upper butts across said gap the face 64 shall engage the inner face of the block 34 even though the jacks 15 have been rocked outwardly somewhat, say under the action of centrifugal force, in the crossing of the gap. It will be appreciated that the upper butts of all the jacks are provided with the inclined face 64, as under the action of its selector at the point 10, the upper butt of any one of the jacks may have to pass across the said gap.

From the foregoing it will be noted that the jacks 18, 20, 22, 24 which are rocked inwardly by their selectors at the point 10 are not rocked outwardly again until after they have passed the incline 52 when they are lifted by the incline 40 to operate their needle sliders so that the corresponding needles knit at one of the feed points. 30 It will be noted also that the jacks 17, 19, 21, 23, 25 which are not rocked inwardly at 10 are lifted by the incline 52 with the result that the needles associated with these jacks knit at the other feed point of the machine and that thereafter 35 these jacks are rocked inwardly before they reach the incline 40. Thus, the jacks that are lifted by the incline 40 are not lifted by the incline 52, while those that are lifted by the incline 52 are not lifted by the incline 40. To permit the jacks 40 18, 20, 22, 24 to pass by the cam block 56 and yet remain rocked forward, the block 56 is cut away at 58 to provide room for the upper butts of these jacks.

In a modification, the inclined surface 54 on the block 56 is dispensed with and instead the edge 45 66 (Figure 2) of the block 56 is chamfered off. With such a construction, the jack will be rocked inwardly, as it is moved down by the incline 60, owing to the action of the chamfer on the upper butt of the jack.

In Figure 14, the pilot cams corresponding to the pilot cams 155 and 156 are indicated at 190 and 192, respectively, while 194 is the stitch cam for the main feed point and 196 is the stitch cam for the additional feed point. The idle track in which the knitting butts of the needle sliders travel at times, is indicated at 198, the knitting tracks for the main feed point and the additional feed point being indicated at 200 and 202 respectively. The single needle selecting mechanism which only is required in this construction is located at 10.

In the second construction of needle-selecting mechanism according to the present invention which is illustrated in Figure 11, the pattern drum 82 instead of being arranged with its axis parallel with that of the needle cylinder, as in the first construction, has its axis at an angle to the axis of the cylinder. In the particular example under consideration the axis of the drum intersects the axis of the cylinder and makes an angle of about forty-five degrees with the cylinder axis. In other respects the drum is similar to the pattern drum of the construction herein first described and has co-operating with it a similar

series of levers 120, and is driven in a similar manner. The selectors 124 in this construction are arranged in tricks formed in a conical bed 180 which is secured to the gear wheel 80 which, as before mentioned, is attached to the needle 5 cylinder 78. The cam 182 which actuates the pawl and ratchet mechanism (indicated generally at 184) for driving the drum 82 is carried upon this conical bed 180. The surface of the conical bed is that of substantially a ninety degree 10 cone and as it is symmetrical about the cylinder axis, adjacent parts of the drum periphery and of the surface of the conical bed are substantially parallel to one another. The upper end of each selector is so formed as to have a substantially 15 vertical surface 184 for engaging a similar surface on the jack 186 which surface takes the part of the incline 139 on the jack 128 of the first construction. In the jack now being described, the lower part or stem 188 is received 20 behind a part of the conical bed 180 and the part of the jack about the upper butt 135 is somewhat longer than in the first construction to allow for the fact that the jack is generally lower in the cylinder owing to the inclined position of 25 the pattern drum 82.

In operation, this construction is similar to the first construction and a description of its operation is therefore deemed unnecessary, but it may be mentioned that when a selector 124 is 30 moved upwardly by the action of the cam incline 122 of the associated lever 120 upon the butt 123 of the selector, the jack 186 is moved inwardly by the selector and the upper butt 135 of the jack is thereby removed from over the cam surface 137, and that in this construction the selector 124 is returned to its initial position by being forced downwardly by the jack as the jack is moved outwardly by the cam surface 138 acting upon its lower butt 136. 40

Although the needle-selecting mechanism and the cam assemblage for the jack have been herein described as applied only to the plain needle cylinder of the machine, it will be appreciated that the said mechanism and assemblage may 45 equally well be applied to the rib needle cylinder of the machine or even to both of said cylinders.

We claim:

1. In a circular knitting machine, a needle cylinder having tricks therein, a needle slider and a jack for operating the slider, both located in one and the same trick of the needle cylinder, a cam for operating said jack, a conical bed stationary in relation to the needle cylinder, tricks in said bed, a selector in one of the tricks in 55 said bed, and pattern means for moving said selector lengthwise of said trick, whereby said selector moves the jack from engagement with its operating cam.

2. In a circular knitting machine, a needle 60 cylinder having tricks therein, a needle slider, a jack for operating the slider, and a selector for controlling the jack, all located within one and the same trick of the needle cylinder, a jack-operating cam, and pattern means for moving the selector lengthwise of said trick to move the jack out of engagement with the jack-operating cam.

3. In a circular knitting machine, a pattern 70 drum, a stud upon which said pattern drum is rotatably mounted, a recess in an end of said drum into which recess a part of said stud projects and a spiral spring surrounding said part of the stud, said spring being held in compression between the bottom of said recess and 75

the end of said part by means located at said end.

4. In a circular knitting machine, a needle slider, a jack for moving said slider, two butts on said jack arranged at different levels on said jack and mutually disposed substantially at right angles, cam means for operating said jack, said cam means including a cam for imparting slider-operating movement to said jack with which cam one of said butts is adapted to engage, means for moving the jack to remove said butt from engagement with said cam, and a second cam adapted to engage the other one of said butts and thereby to restore the first named butt to operative relation with the first named cam, said butts being mutually disposed substantially at right angles and being adapted to straddle said cams.

5. In a circular knitting machine, a needle slider, a jack for moving said slider, two butts on said jack arranged at different levels on said jack and mutually disposed substantially at right angles, cam means for operating said jack, said cam means including a cam for imparting slider-operating movement to said jack with which cam one of said butts is adapted to engage, means for moving the jack to remove said butt from engagement with said cam, and a second cam adapted to engage the other one of said butts and thereby to restore the first named butt to operative relation with the first named cam, said butts being mutually disposed substantially at right angles and being adapted to straddle said cams, one of said butts having a cam engaging surface inclined at an acute angle to another cam engaging surface thereon, whereby the jack by reason of said inclined surface is enabled to cross a gap in said cam means, into which gap the said butt would otherwise tend to enter.

6. In mechanism for selecting and operating the needles or needle sliders of circular knitting machines, the combination with a plurality of jacks, each jack being operatively connected with a needle or needle slider and having two butts mutually disposed substantially at right angles, of selecting mechanism for each jack, said mechanism comprising cam means provided with cam surfaces for cooperation respectively with the jack butts, said butts being arranged to straddle said cam means, and a selector for moving said jack to remove one of said butts from operative relation with the associated cam surface, the other of said cam surfaces being constructed and arranged for cooperation with the other of said butts to return said jack and position said first butt in operative relation with the associated cam surfaces.

7. In a circular knitting machine, a needle

cylinder having tricks therein, a needle slider, a jack for operating the slider, and a selector for controlling the jack, all located within one and the same trick of the needle cylinder, a jack-operating cam, and pattern means for moving the selector lengthwise of said trick to move the jack out of engagement with the jack-operating cam, said selector and jack being provided with cooperating cam surfaces for effecting displacement of said jack laterally of the path of movement of said selector.

8. In mechanism for selecting and operating the needles or needle sliders of circular knitting machines having two feed points, the combination with a plurality of jacks, each jack being operatively connected with a needle and having two butts, of selecting and operating mechanism for each jack, said mechanism comprising cam means provided with cam surfaces for cooperation respectively with the jack butts, said butts being arranged to straddle said cam means, and a selector for moving said jack to remove one of said butts from operative relation with the associated cam surface to render the jack inoperative for needle actuating movement thereby, the other of said cam surfaces being constructed and arranged for cooperation with the other of said butts to return said jack and position said first butt in operative relation with the associated cam surface, said cam means including a further cam surface constructed and arranged to impart needle actuating movement to said jack in the event the latter is not moved by the selector, each of said cam surfaces being effective to impart needle actuating movement to said jack to affect the associated needle at one only of said feed points.

9. In a circular knitting machine, the combination with a rotating needle cylinder, of a plurality of needle controlling jacks carried by said cylinder, at least two stationary cams having adjacent portions thereof spaced circumferentially and generally axially of the needle cylinder to provide a gap therebetween, each jack being provided with at least one laterally directed butt having a surface extending generally radially of the axis of the needle cylinder for engagement by at least one of said cams, said butt being further provided with an outer face inclined at an acute angle with respect to the radial for engagement with the inner faces of the cams, the inclination of this outer face being inward in the direction of the axial spacing of the following cam from the leading cam, whereby the butt may more readily pass over the gap between the cams.
